O. WILLIAMS.
SIGNAL FOR RAILROAD CROSSINGS.
APPLICATION FILED APR. 8, 1915.

1,250,065.

Patented Dec. 11, 1917.

UNITED STATES PATENT OFFICE.

OLIVER WILLIAMS, OF EMPIRE, ALABAMA

SIGNAL FOR RAILROAD-CROSSINGS.

1,250,065.

Specification of Letters Patent. Patented Dec. 11, 1917.

Application filed April 8, 1915. Serial No. 19,977.

To all whom it may concern:

Be it known that I, OLIVER WILLIAMS, a citizen of the United States, residing at Empire, in the county of Walker and State 5 of Alabama, have invented certain new and useful Improvements in Signals for Railroad-Crossings; and I do hereby declare the following to be a full, clear, and exact description of the invention, such as will enable others skilled in the art to which it 10 applies to make and use the same.

The invention relates to improvements in signals for railroad crossings.

The object of the present invention is to 15 improve the construction of signals for railroad crossings and to provide a simple, practical and efficient railroad crossing signal equipped with a signal flag adapted to be operated by a train at a distance from a 20 crossing and capable, after the train has passed, of automatically dropping out of sight for indicating that the railroad track may be crossed with safety.

With these and other objects in view the 25 invention consists in the construction and novel combination and arrangement of parts hereinafter fully described, illustrated in the accompanying drawings and pointed out in the claims hereto appended, it being 30 understood that various changes in the form, proportion and minor details of construction may be resorted to without departing from the spirit or sacrificing any of the advantages of the invention.

35 In the drawings

Figure 1 is a plan view of a safety railroad crossing signal constructed in accordance with this invention.

Fig. 2 is a side elevation of the same,

40 Fig. 3 is a detail sectional view on the line 3—3 of Fig. 2.

Fig. 4 is a detail perspective view of the 45 depressible train actuated device.

Fig. 5 is a detail view of the depressible train actuated device illustrating a modification of the invention.

Like numerals of reference designate corresponding parts in all the figures of the drawings.

50 The approach of a train is indicated at a crossing by a danger flag 7 located at one side of the crossing and secured to an arm 8 of a rock shaft 9 consisting of a series of rods coupled together by sleeves 10 and 55 journaled in suitable bearings 11 of stands 12. The stands 12 which are provided at the

bottom with base or attaching flanges 13 are secured to the upper faces of the cross ties and may be arranged at any desired intervals. The rock shaft is provided at its outer 60 ends with an operating arm or crank composed of spaced sides 14 and 15 and a connection portion 16 and adapted to be swung downwardly by a depressible device 17. The side 14 of the crank or operating arm is secured to the adjacent end of the rock shaft and the other side 15 is provided at its inner end with a pivot 18 mounted in a bearing 19 of a stand or bracket 20. The depressible device 17 is adapted to be actuated 70 by the wheels of a passing train consists of a plate or body portion of substantially segmental form normally projecting above the tread of the adjacent rail and presenting an upper rounded or convex 75 face 21 to the wheels of a train. The depressible train actuated device is provided with depending substantially L-shaped arms 22 extending to and connected with the transverse connecting portion 16 of the crank 80 of the rock shaft.

In practice the parts will be of proper proportion to secure the desired throw of the flag carrying arm which is provided with a weight 23 preferably in the shape 85 of a ball for returning the flag carrying arm to its lowered position after a train has passed. Also any other suitable signaling device may be applied to the arm 8. Also in practice the flag and operating mechanism will be located at each side of the crossing for indicating the approach of a train from either direction. Ordinarily the operating device will be located at or adjacent to the whistle board so that ample time will 90 be afforded for persons at the crossing to get out of the way of an approaching train. The depressible train actuated device may be constructed in any suitable manner so as to present a substantially rounded or convexed face to the wheels of a train and spaced arms or portions for connection with the crank of the rock shaft.

The flag may be of any desired design and may bear any inscription and it may 105 consist of the ordinary red danger signal flag employed on railroads.

In Fig. 5 of the drawing is illustrated a modification of the depressible train operated device. This device consists of a 110 curved resilient bar or spring 24 provided at its ends with eyes 25 and having spaced

centrally arranged approximately L-shaped arms 26 adapted to be connected with the crank arm of the rock shaft. The eyes at the ends of the curved bar or spring 24 enable the same to be mounted in any desired manner.

What is claimed is:—

1. A safety railroad crossing signal including a longitudinal rock shaft provided adjacent to the crossing with an arm, a danger signal carried by the arm, a crank member connected with the rock shaft, and a depressible train operated device consisting of a body having a rounded upper face and an arm extending from the body and connected with the said crank member.

2. A safety railroad crossing signal including a rock shaft designed to be mounted at one side of a track and provided adjacent to the crossing with an arm and having a weight and provided with a signal flag, a crank connected with the rock shaft and composed of spaced sides and a con-

nnecting portion, and a depressible train actuated device located adjacent to the track 25 and having an arm connected with the said crank.

3. A safety railroad crossing signal including a rock shaft designed to be arranged at one side of a track and provided adjacent 30 to the crossing with an arm, a signal carried by the arm and extending from the rock shaft in one direction, a crank extending from the rock shaft in the opposite direction and composed of spaced sides and a 35 connecting portion, and a depressible train actuated device consisting of an approximately segmental body portion and spaced L-shaped arms extending from the body portion to the connecting portion of the crank. 40

In testimony whereof I affix my signature in presence of two witnesses.

OLIVER WILLIAMS.
